US0D1111161S

(12) **United States Design Patent** (10) Patent No.: **US D1,111,161 S**
(45) Date of Patent: ** Feb. 3, 2026

(54) **CARTRIDGE FOR INHALER**

(71) Applicant: **Merxin Limited**, King's Lynn (GB)

(72) Inventor: **Graham Purkins**, Norfolk (GB)

(73) Assignee: **Merxin Limited**, King's Lynn (GB)

(**) Term: **15 Years**

(21) Appl. No.: **29/880,452**

(22) Filed: **Jul. 24, 2023**

Related U.S. Application Data

(62) Division of application No. 35/514,179, filed on Feb. 3, 2022 (U.S. filing date under 35 U.S.C. 384), and having an international filing date of Feb. 3, 2022.
